UNITED STATES PATENT OFFICE

WILLIAM C. BAXTER, OF BEVERLY, MASSACHUSETTS, ASSIGNOR TO UNITED SHOE MACHINERY CORPORATION, OF PATERSON, NEW JERSEY, A CORPORATION OF NEW JERSEY

SPLITTING MACHINE

Application filed November 27, 1929. Serial No. 410,160.

This invention relates to splitting machines and is herein illustrated as embodied in a machine adapted to split the heel end of a shoe sole to form a flap which, in the finished shoe is bent down and attached to the breast of a wooden heel.

In machines of this type the sole is commonly pressed against a support in a locality close to the edge of a knife, and then either 10 the blank or the knife is moved first in a direction to cause the knife to enter the blank to form the flap, and then in the opposite direction to cause the knife to be withdrawn from the blank. It is desirable that, when 15 the knife is being withdrawn from the blank, the pressure upon the blank should be relieved, since at that time the thin flap has already been formed and is liable to be distorted. According to one feature of the invention 20 the construction of the machine is such that the pressure may be relieved during the time that the blank is being withdrawn. In the illustrated machine the knife is a stationary one, and the blank is fed over a work 25 table to the knife by a feed roll which is rotated first in one direction and then in the other. The roll presses the blank against the table in a locality close to the edge of the knife and acts first to feed the blank for a 30 given distance to the knife to cause the knife to enter the blank and then to withdraw the blank from the knife. During this withdrawal, after the flap has been formed, the work table is dropped slightly so as to relieve 35 the pressure upon the blank.

In prior application Serial No. 223,968 filed in my name October 4, 1927, which has become United States Letters Patent No. 1,747,282, there is disclosed a sole having at its rear end two flaps, a very thin flap which is all grain and is designed to be torn off and discarded after the shoe in which the sole is incorporated has been nearly finished, and a thick flap partly of grain and partly of flesh 40 which is designed to be attached in the usual manner to the breast of a wooden heel. The thin flap serves merely as a protective covering for the adjacent surface of the thick flap during the manufacture of the shoe. According to another feature of the invention 45

mechanism is provided for automatically forming a plurality of flaps on a blank when desired. In the illustrated machine the blank is caused to be operated upon to produce in it two cuts, the position of the blank with reference to the knife being changed between the times the cuts are made to locate the cuts at different levels in the blank so as to produce two flaps. 55

In order to facilitate the proper presentation of a blank to the feeding means there is provided in combination with means for feeding a blank to and from the knife, means for presenting the blank to the feeding means. In the illustrated machine this presenting mechanism takes the form of a slide which is driven from the roll which feeds the blank to and then withdraws it from the knife so that, when the feed roll rotates in one direction the slide moves forward, and when the direction of the roll is reversed, the slide moves back into initial position. 60

These and other features of the invention including certain details of construction and combinations of parts will be described as 65 embodied in an illustrated machine and pointed out in the appended claims. 70

Referring now to the accompanying drawings,

Fig. 1 is a side elevation of a machine in 80 which the present invention is embodied;
Fig. 2 is a front elevation of the machine;
Fig. 3 is a plan of the machine;
Fig. 4 is a vertical section on the line 85 IV—IV of Fig. 3, certain parts being shown in full lines;

Fig. 5 is a perspective showing more particularly the reciprocating slide which presents the soles to the feed roll;

Fig. 6 is a perspective of the mechanism 90 for shifting a cam roll from one cam to another;

Fig. 7 is a front elevation of this same shifting mechanism showing also the roll and the cams; 95

Fig. 8 is a sectional view of one of the cams;

Fig. 9 is an elevation of the other cam; and

Fig. 10 is a perspective of the heel end of 100 a sole having formed upon it two flaps.

The illustrated machine is capable of forming upon a sole 100 (Fig. 10) two flaps, a comparatively thick flap 300 which is bent down and attached to the breast of a wooden heel in the finished shoe and a very thin flap 200 which serves to protect the adjacent surface of the thick flap during the manufacture of the shoe and is torn off at the end of the manufacture. By this procedure the surface 5 of the thick flap which is exposed in the finished shoe does not need the usual buffing operation to clean it. As will be explained later the machine may also be operated to produce upon a sole a single flap; and in either 10 case two soles may be operated upon at the same time.

Referring first to Figs. 4 and 5, two soles 100 are fed twice forward and back over a table 11 to a stationary knife 13, the soles 20 being thus twice presented to the knife and twice withdrawn therefrom in such manner that the two cuts form respectively the two flaps 200, 300 (Fig. 10) referred to above, the thin flap 200 being preferably composed 25 entirely of grain and the thick flap 300 partly of grain and partly of flesh. The knife is held in fixed position; and the location of any given cut in the sole depends upon the level or height of the table 11 above the edge 30 of the knife. In Fig. 10 the sole is shown grain side up; but in the machine the soles are fed grain side down over the table to the knife. During the first cut the table is in lowered position to make the cut which is 35 lowermost in Fig. 10. The table is then raised and held raised while the cut is made which is uppermost in Fig. 10. In other words there is first produced a flap equal in thickness to the combined thicknesses of the 40 flaps 200, 300; and then upon this flap is formed the thin flap 200.

The soles are presented over the table 11 by a feed slide, which will be described later, to a feed roll, said roll then acting to feed 45 the soles to and withdraw them from the knife twice. Referring still to Fig. 4 the feed roll is an internally yielding one comprising a series of metallic rings or sections 15 mounted upon a layer of rubber 17, the 50 rubber being mounted upon a layer of canvas 19 which is in turn mounted upon the shaft 21 of the roll. Fast to the shaft at each end of the roll is a hub; and mounted in these hubs and extending lengthwise of the roll 55 just outside the rubber layer 17 are three bars 23, shown in cross-section in Fig. 4. Each metallic section 15 has in its inner edge three notches which are slightly larger in cross-section than are the bars. The roll is thus 60 a yielding, sectional one particularly adapted to this type of splitting machine in which the soles are supported upon an unyielding work table during the splitting operation. As has been explained, the thickness of the 65 flaps produced is determined by the height

of the work table, the edge of the table adjacent to the knife being thus a gaging edge. The yielding roll holds all parts of the soles in the locality of the knife flat against the table irrespective of whether the soles are of 70 uniform thickness. It will be understood, however, that the two soles which are being fed at any given time are of approximately the same thickness.

The shaft 21 of the roll (Fig. 1) is rotatably mounted in an arm 25 which is pivoted about the axis of a rock-shaft 27 so that the roll may be swung about the axis to adjust the height of the roll above the work table to provide for soles of different thicknesses. The roll is held in adjusted position by two rods 29, 31 (Fig. 2) which are connected respectively with the feed roll shaft 21 near opposite ends of that shaft. Inasmuch as these rods and their mountings are 80 substantially alike only one of them will be described in detail. The rod 29 (Figs. 1 and 2) at its upper end is threaded into a depending stem 33 of a collar 35 which is loose on the roll shaft 21. At its lower end the rod 29 (Fig. 4) passes loosely through a sleeve 35 and has at its lower end a nut 37 between which and the lower end of the sleeve 35 is a coiled spring 39. The sleeve 35 is threaded through a cross-bar 41 which is fast to the 90 legs of a yoke 43, said yoke having a horizontal bore to receive an eccentric 45 fast to a rock-shaft 47. The rod 31, as may be seen by an inspection of Fig. 2, is mounted in the same manner as the rod 29. When, therefore, the 95 shaft 47 is turned in one direction or the other, the eccentrics act to pull down or push up on the rods 29, 31 and thereby to lower or to raise the feed roll. In order to provide means for turning the shaft 47, said shaft has fast to it a worm gear 49 (Fig. 4) which meshes with a worm 51 fast to one end of a short rotary shaft to the other end of which is fastened a hand wheel 53. The feed roll is thus normally held down in the position shown by the coiled spring 39 on the rod 29 and the similar coiled spring on the rod 31; and the tension of these springs may be varied by turning the sleeve 35 through which the rod 29 passes or the similar sleeve through 100 which the rod 31 passes.

As has been stated above, the work is fed to the knife to cause a cut to be made in the work and is then withdrawn from the knife. In order to produce this alternate infeeding and outfeeding, the feed roll is rotated first in one direction, and then in the reverse direction. To this end (Fig. 1) a gear 55 fast to the feed roll shaft 21 is engaged by a segmental rack 57 carried at the outer end of an arm 59 the inner end of which is fast to the rock-shaft 27. Pivoted at 61 to this arm is the upper end of a link 63 the lower end of which has pivoted to it a square block 65 (Fig. 7) said block 105

being adjustable in a radial guideway in a heavy disk 67 which is fast to a horizontal rotary shaft 69 to which either one revolution or two revolutions may be imparted as will presently appear. The position of the block 65 in the radial guideway determines the throw of the link 63, the amplitude of angular movement of the arm 59 and the extent of rotation first in one direction and then in the other of the feed roll. In order to adjust the block 65 in the radial guideway in the disk 67, a screw 71 is threaded through the block, said screw having at the end nearest the block a square head 73 by which it may be turned. The other end of the screw has an enlarged end 75 which is received in a bore in the solid disk 67 said head being provided with a circumferential groove 77 into which extends the end of a small screw 79 threaded through one side of the disk. The screw 71 is thus rotatably mounted in the disk but held from longitudinal movement; and, when the screw is turned, the block 65, which is pivotally mounted on the lower end of the link 63, is moved toward or from the center of the disk.

The table 11 which has a hardened plate set into it beneath the feed roll (Figs. 3, 4 and 5) and over which the soles are fed to the knife, is adjustable up and down to determine the thickness of the flap or flaps to be produced and may also be moved up or down or both during the operation of the machine, as will presently be described.

The work, which in the illustrated machine consists of the two soles, is advanced over the work table by a feed slide which is operated forward and back by two gears on the feed roll shaft said gears meshing with racks on the feed slide. Fastened to the frame of the machine (Fig. 2) near one side of the frame is a bracket 81, said bracket being fastened by means of cap screws 83; and similarly fastened to the frame at the other side of the machine is another bracket 85. The bracket 81 carries at its top a horizontal guide bar 87 having in its upper part a groove rectangular in cross-section, there being a thin plate 89 fastened to the bar and extending over part of the groove to form a guideway for the suitably shaped lower portion of a rack-bar 91. The bracket 85 carries at its top a guide bar 93 similar to the guide bar 87 and provided with a thin plate 95 similar to the plate 89 to form a guideway for a second rack bar 97 similar to the rack bar 91. Referring now to Fig. 5, the guide bar 93, the plate 95 and the rack bar 97 are shown in perspective. The two rack bars 91, 97 (Fig. 3) are connected at their rear ends by a plate 99 the down-turned ends of which are fastened respectively by screws 101 and 103 to the rack bars. Formed in this plate 99 is an undercut guideway 105

in which is slidably mounted the stem of a carrier 107 for the grippers which engage the soles. The stem of the carrier has in it a slot 109 through which passes a short upright adjusting shaft 111. This shaft (Fig. 4) extends down through the plate 99 and has a headed screw 113 at its lower end. About half way up on the shaft 111 is fastened a small gear 115 which rests upon the top of the stem of the carrier 107 and meshes with a rack 117 which is fast to said stem. A locking pawl 119 is pivoted at 121 to upstanding lugs formed on a small block 123 which is adjustable in a groove 125 in the plate 99 and is held in adjusted position by a cap screw 127 the stem of which passes through a slot in the block 125 and is threaded into the plate 99. The locking pawl 119 has teeth to engage teeth formed on the rack-bar 117 on the opposite side of the bar from the teeth which are engaged by the small gear 115. A spring (not shown) which is coiled about the small pivot 121 of the locking pawl and has one end resting upon the plate 99 and the other end bearing against the under side of the tail of the pawl normally holds the pawl in operative position. By pressing upon the tail of the pawl and turning the thumb-hold 129, which is fast to the small upright shaft 111, the carrier 107 may be adjusted forward and back; and, when the pawl is released, the carrier is locked in adjusted position.

Referring now more particularly to Figs. 3 and 5, the mounting upon the carrier 107 of the means for gripping the soles 100 will be described. Mounted in suitable bearings in the carrier 107 is a horizontal rock-shaft 131, and fast to the carrier 107, below the rock-shaft, are two thin flat plates 133, 135 each of which is the stationary member of a pair of grippers. The toe ends of the soles are held respectively against the plates 133, 135 by angularly movable grippers 137, 139. These grippers are loosely mounted upon the rock-shaft 131 and urged at all times to move in a direction to press the toe ends of the soles against the plates 133, 135 by springs 141, 143 which are coiled about the rock-shaft 131 and have their lower free ends resting upon the carrier 107 and their upper free ends engaging respectively the gripper 137 and the gripper 139. The gripper 137 has a thumb piece 145 depression of which lifts the gripper; and the gripper 139 has a similar thumb-piece 147. Thus either gripper may be raised independently of the other if desired. In order to permit the two grippers 137, 139 to be lifted together, there is fast to the middle of the rock-shaft 131 by means of a pinch-screw 149 a block 151 carrying a pin 153 the opposite ends of which extend respectively beneath the grippers 137, 139; and fast to the rock-shaft 131 is a third

thumb-piece 155 by which the shaft may be rocked to raise the grippers together.

The feed slide, which comprises the racks 91, 97, the plate 99, the carrier 107, the rock-shaft 131 and the two pairs of grippers 133, 137 and 135, 139 is moved forward and back in a manner presently to be described; and means are provided for raising the grippers 137, 139 automatically, if desired, at the end 10 of the backward stroke of the slide in order to free the soles which have just been operated upon and to permit two other soles to be placed with their toe-ends upon the plates 133, 135. This means comprises (Fig. 5) an 15 arm 157 fast at its upper end to the rock-shaft 131, a toothed bar 159 and a stop 161. The bar 159 is pivoted at one end at 163 to the stationary guide 93 and passes through a slot in the lower end of the arm 157, being supported at that locality by a smaller roller (not shown) mounted upon a pin 165 which passes through the slotted end of the arm 157. The stop 161 is slotted in its upper portion and has pivoted at 167 a spring-pressed pawl 20 25 169 which engages the teeth on the bar 159. By pressing upon the tail of the pawl to free it from engagement with the teeth, the stop 161 may be adjusted into desired position on the bar 159. This stop, when used, is ad- 30 justed into such a position that the arm 157 contacts with the stop just before the feed slide reaches the limit of its backward stroke so that, when the feed slide is completely re- 35 tracted, the grippers 137, 139 are raised. This stop is preferably used only when a single flap is being cut, and the feed slide therefore makes but one reciprocation.

The racks 91, 97 of the feed slide are driven from gears 171, 173 (Fig. 3) which are fast 40 to the feed roll shaft 21 one near each end of said shaft. Inasmuch as the two connections between the gears 171, 173 and the racks 91, 97 are substantially alike, only one of them will be described in detail. Referring 45 first to Fig. 4, the rack 91 meshes with a pinion 175 which is driven from a second pinion 177, said second pinion being driven from the gear 171 on the feed roll shaft. The pinions 175, 177 are rotatably mounted in an 50 arm 179, the hub of which (Fig. 3) encircles the feed roll shaft 21. The purpose of this construction is to permit the feed roll to be adjusted up and down in the manner which has been described without disturbing 55 the driving connections between the feed roll and the racks of the feed slide. In order to hold the pinion 175 always in mesh with the rack bar 91, a depending portion of the arm 171 has a roll 181 which runs in a horizontal guideway. The guideway for the roll 181 is not clearly shown in Fig. 4; but the corresponding guideway for the roll which corresponds to the roll 181 on the other side of the machine is shown in Figs. 1 and 5 at 60 65 183, the upper wall of the guideway being

formed by the under side of the plate 95. It will be understood that the extent of up and down adjustment of the feed roll is not great; and that the extent of horizontal movement of the roll 181 is very small. In Fig. 1 the two pinions 377 and 375 which correspond to the pinions 177 and 175 are shown.

With this construction, each time the feed roll is rotated first in one direction and then in the other, the soles are first fed to the knife and then withdrawn therefrom. Assuming that the extent of oscillation of the feed roll is uniform the lengths of the cuts formed in the soles are determined by the original position of the soles; and this position may be varied by adjusting the grippers 135, 139 and 137, 133 (Fig. 5) toward or from the feed roll by rotating the small upright shaft 111 in the manner which has been described. It will be noted that what is really determined is the distance from the toe end of the sole to the inner end of the cut, since the soles, as shown in Fig. 4, always have their toe ends in contact with a vertical face on a downwardly extending lug of the carrier 107 on which the grippers are mounted.

As has been explained above the thickness of the flap produced by a cut of the knife depends upon the level of the table 11 at the time the cut is made. In order to permit the level of the table to be changed so as to determine the thickness of a flap as well as to relieve the pressure of the feed roll upon the work during the backward stroke of the table when the work is being withdrawn from the knife, the table is mounted for up and down movement.

Referring more particularly to Figs. 2 and 4, the table 11 is bolted to the upper horizontal portion of an angle-plate 185, the depending portion of the plate being slidably mounted in a carrier 187, which in turn is pivoted at 189 to the frame of the machine. The carrier 187 (Fig. 2) is held in adjusted angular position about the axis of the pivot 189 by cap screws 191 which pass through slots in the carrier and are threaded into the frame of the machine. The lower end of the carrier 187 is cut away to produce a sort of fork between the arms of which extends a boss 190; and adjusting screws 192 threaded through lugs on the carrier 187 engage this boss. By this means a very fine adjustment of the carrier may be made. The purpose of making the carrier, and with it the work table, adjustable about the pivot 189 is to make it possible to bring the inner edge of the table into parallelism with the adjacent edge of the knife even though the edge of the knife, due to imperfect grinding or to some other cause, is not exactly horizontal. It will be understood that the extent of this adjustment is usually very small, but that the capability for such adjustment is highly de-

sirable since some of the flaps which are produced upon soles are not more than five one-thousandths of an inch thick.

The depending portion of the angle plate 185, which supports the work table 11, is 5
slidable up and down upon the carrier 187, as has been stated, its side edges being engaged and guided by ribs formed along the 10
sides of the carrier, and said depending portion being held down upon the carrier by narrow plates 193 which are fastened by bolts 195 to the tops of the ribs on the carrier. The angle plate 185 has at its lower edge a hardened plate 197 with which contacts an 15
adjusting screw 199. By setting this screw in different positions the extent to which the work table may descend may be controlled.

In producing the two flaps 200, 300 shown in Fig. 10 the sole is fed, with the grain side 20
(the upper side in Fig. 10) down, over the work table 11. During the first oscillation of the feed roll the cut between the flap 300 and the sole is made to produce a flap equal 25
in thickness to the combined thicknesses of the flaps 200, 300. Ordinarily this first flap is about thirty-five thousandths of an inch thick. Before the second cut is made the work table is raised so that the flap 200 is 30
very thin, being commonly about five thousandths of an inch thick.

In the position of parts shown (Fig. 4) the screw 199 is supporting the work table 11 in position to produce the first cut in the soles. During the first revolution of the shaft 69 35
and the first reciprocation of the soles this first cut is made in each sole to produce a flap equal to the combined thicknesses of the two desired flaps. During the second reciprocation of the soles, the table 11 is raised by a 40
bell-crank lever 201, held in raised position during the cuts which produce the thin flaps 200 on the soles, and is then lowered slightly to relieve the pressure upon the soles so that the thin flaps will not be stretched or otherwise 45
distorted during the withdrawal of the soles from the knife.

The horizontal arm of the bell crank lever 201 extends through an opening in the angle plate 185 and has threaded through its outer end a screw 203 which engages a second hardened plate 205 on the angle plate. During the first cut when the work table 11 is held in lowered position the bell crank lever does not actuate the table 11 at all; but, just before 55
the second cut, it raises the table as has been explained.

The mechanism which moves the bell-crank lever 201 in the manner described above will now be described. The downwardly extending arm of the bell-crank lever 201 carries a roll 207 (Fig. 4) which may run on either one of two cams, mounted upon the shaft 69. Referring to Fig. 7, the two cams on the shaft 69 are indicated respectively at 209 and 211. The depending arm of the

bell-crank lever 201 is forked as shown and has mounted in aligned holes in the ends of the forks a sleeve 213 upon which is rotatably mounted the roll 207. This roll, which is also slidable on the sleeve 213, is held in the position shown, in which it runs on the roll 209, by a rod 215 having a radial pin 217 which projects through a slot 219 in the sleeve into an internal circular groove in the roll 207. Thus, by moving the pin horizontally, the roll 207 may be shifted into contact with the cam 211 and back again into contact with the cam 209. The cam 209 has no effect upon the work table 11 during the first cut; but is effective, as will presently be explained when a single cut and a single flap are to be produced.

The mechanism for moving the rod 215 to shift the roll 207 is shown best in Figs. 6 and 7. On the end of the shaft 69, which, as has been stated, may be caused to make two revolutions so as to present the soles to and withdraw them from the knife twice, is fast a gear 221 which meshes with a gear 223 of twice its size so that two revolutions of the gear 221 cause one revolution of the gear 223. This gear 223 is fast to a barrel cam 225 which is rotatably mounted upon a short stationary shaft 227, being held thereon by a collar 229 fastened to the shaft by a set screw 231. The cam 225 has in its periphery a cam track 233 into which projects a small roll 235 carried at the outer end of a small rod 237 which is slidable mounted in an upright lever 239 pivoted at its lower end about a rod 241 carried by a stationary bracket 242. The small rod 237 has fast to it a collar 243 and a head 245, the rod together with the small roll 235 being held in the position shown by a plate 247 adjustably mounted upon the bracket 242 by means of a cap screw 249 the stem of which passes through a vertical slot in the plate and is threaded into the bracket. It should be noted that this plate 247 has a notch in its upper edge, and that by loosening the cap screw 249, lowering the plate, pulling out the rod 237 until the collar 243 is outside the plate, and then raising the plate, the roll 235 may be held withdrawn from the cam track 233 when desired. The purpose of doing this, as will be described later, is to cause the soles to be fed to and from the knife once so as to produce upon each sole a single flap; and in this case the height of the work table 11 is governed by the cam 209. The upper end of the lever 239 carries the stem of a collar 251 which encircles the rod 213 and has in it a bore considerably larger in diameter than that of the rod so that the rod may move 100
somewhat in directions at right angles to its longitudinal axis. Fast to the rod 215, one on each side of the collar 251, are two collars 253, 255 so that, when the lever 239 is swung 105
about its pivot 241, the rod 213 is moved back 110
115
120
125
130

130

and forth in the direction of extent of its axis.

Referring now to Fig. 7, which shows the parts of the machine in their normal position of rest, the cam track 233 is so shaped that when one revolution is imparted to the cam 225 by two revolutions of the shaft 69, the roll 207 remains opposite the cam 209 until nearly the end of the first revolution. It is then shifted into contact with the cam 211 and remains in that position until nearly the end of the second revolution of the shaft 69 whereupon it is returned to the position shown as the machine comes to rest.

During the first revolution of the shaft 69 the soles are first fed to the knife and then withdrawn therefrom. During the making of this first cut the work table remains at its lower level with the hardened plate 197 on the angle-plate 185, to the upper portion of which the table is fast, resting upon the screw 199 (Fig. 4). During the withdrawal of the soles from the knife the roll 207 is shifted to the right (Fig. 7) into operative relation with the low part of the cam 211 (Fig. 9). During the first part of the forward movement of the soles for the second time, the roll 209 rides up on the high part of the cam 211 whereby the work table is raised and held raised during the forming of the thin flaps 200 on the soles. Just at the end of this second cut, the roll 209 rides down again upon the low part of the cam 211 thus relieving the pressure upon the soles during the withdrawal of the soles from the knife. During this withdrawal the roll 207 is shifted back opposite the cam 209, and the table drops until arrested once more by the screw 199.

Referring more particularly to Figs. 1 and 4 the mechanism for driving the shaft 69 will be described. Referring first to Fig. 1, a gear 257 is driven continuously through a worm 259, a large gear 261 and a small gear 263, said latter gear being fast to the shaft of an electric motor 265. Referring now to Fig. 4, the gear 257, which is driven in the direction indicated by the arrow has internal teeth 267 which may be engaged by a dog 269 semi-circular in outline carried by a small shaft 271 which is rotatably mounted in a driven member 273, said member being pinned to the shaft 69. On the outside of the driven member 273 and fast to one end of the small shaft 271, which carries at its other end the dog 269, is a catch 275 which is held in the position shown when the machine is at rest by engagement of an arm 277, said arm being carried by a hub which is loose on the shaft 47, the hub having a projecting lug to which is pivotally attached a treadle rod 279. The lower end of the treadle rod 279 is connected to a treadle 281 by a non-repeat mechanism of well-known construction (Fig. 1) which will not be de-

scribed in detail. It will be understood, however, that when the treadle is depressed the arm 277 (Fig. 4) is first raised and then allowed to fall. When the arm is raised, the catch 275 is rotated in a counterclockwise direction by a tension spring 283 which is connected at one end to the catch and at the other to the driven member 273, the extent to which the catch is moved being limited by contact of the stem of a cap screw 285, which is threaded into the driven member, with the end of a slot formed in the catch. When the catch 275 is thus rotated, the dog 269 is moved angularly into position to be engaged by the internal teeth 267 of the gear 257 and rotation is imparted to the shaft 69. When the arm 277 falls after releasing the catch 275, a roll 287 at the end of the arm runs upon the high part of a cam carried on the periphery of the driven member until nearly one revolution has been completed whereupon the roll rides down upon the low portion of the cam and the arm 277 engages the catch once more to disconnect the driven member 273 from the driving gear 257. As thus far described the clutch is a one-revolution clutch of well-known construction.

In the present machine, the arm 277 is held up in inoperative position until near the end of the second revolution by the movement of the roll 207 (Fig. 7) from the cam 209 to the cam 211. To this end (Fig. 4) there is fast to the hub of the arm 277 a second arm 289 so that the two arms 277, 289 are compelled to move together. This arm 289 projects into the path of sliding movement of the roll 207 so that, when the roll is moved to the right (Fig. 7) before the first revolution of the shaft 69 has been completed, it passes beneath the arm 289 and thus prevents the arm 277 from dropping when, near the end of the first revolution of the shaft 69, it would otherwise be free to drop. Before the end of the second revolution of the shaft the roll 207, as has been explained, is shifted back to the left (Fig. 7) opposite to the cam 209 once more, and in this shifting movement it passes from beneath the arm 289 so that the arm 277 is then free to drop and disconnect the shaft 69 at the end of its second revolution.

In some cases it may be desired to produce only one flap on the end of each sole. In such case (Figs. 6 and 7) the plate 247 is lowered, the pin 237 pulled out, and the plate raised until a notch in its top engages the pin. When the roller 235 has thus been pulled out of the cam track 233 and held in this manner, the roll 207 (Fig. 7) is not shifted to the cam 211 during the first revolution of the shaft 69, and consequently the shaft makes only a single revolution. When a single flap is to be made upon each sole the screw 199 (Fig. 4) is backed off into inoperative position, and the level of the work table

is controlled by the bell-crank lever 201, the position of which in turn is controlled by the cam 209. During the forward movement of the soles the roll 207 rides upon the high part of the cam 209. At the end of the forward movement of the soles, the roll 207 rides down upon the low part of the cam to relieve the pressure of the feed roll upon the soles. When a single flap is thus formed its thickness depends upon the position to which the screw 203 is adjusted in the end of the horizontal arm of the bell crank lever 201.

Although the invention has been set forth as embodied in a particular machine, it will be understood that the invention is not limited in the scope of its application to the particular machine which has been shown and described.

The claims of the present application are restricted to the machine, the method and the article produced forming the subject-matter of prior application Serial No. 223,968 which has been referred to above.

Having thus described my invention, what I claim as new and desire to secure by Letters Patent of the United States is:

1. A machine of the class described having, in combination, a knife, cooperating members one of which is a roll for engaging a blank on opposite sides, first feeding it to the knife and then withdrawing it from the knife, and means for relieving the pressure of the feed members upon the blank during the withdrawal of the blank from the knife.

2. A machine of the class described having, in combination, a knife, a table for supporting a blank, a roll rotatable first in one direction to feed the blank to the knife and then in the reverse direction to withdraw the blank from the knife, the blank being engaged with a given pressure between the roll and the table during the feeding of the blank to the knife, and means for moving the table away from the roll when the direction of rotation of the roll is reversed.

3. A machine of the class described having, in combination, a knife, a roll rotatable first in one direction to feed a blank to the knife and then in the reverse direction to withdraw the blank from the knife, means for adjusting the pressure of the roll upon the blank, and means for decreasing said pressure regardless of said adjustment when the direction of rotation of the roll is reversed.

4. A machine of the class described having, in combination, a knife, means including a rotating roll for engaging the blank with a predetermined pressure and feeding the blank to the knife to produce a split in the blank, means for reversing the direction of rotation of the roll to withdraw the split blank from the knife, and means for relieving the pressure of the feeding means

upon the blank when said direction of rotation is reversed.

5. A machine of the class described having, in combination, a knife, a support for a blank, means for feeding a blank over the support to and from the knife a plurality of times to produce a plurality of cuts, and means operating to change the level of the support between the times that the cuts take place to locate the cuts at different levels in the blank.

6. A machine of the class described having, in combination, a knife, a support for a blank, means for feeding a blank over the support to and from the knife a plurality of times to produce a plurality of cuts, said support being mounted for sliding movement with respect to the plane of the knife, and means for imparting sliding movement to the support between the times that the cuts take place.

7. A machine of the class described having, in combination, a knife, a support for a blank, automatic means for feeding a blank over the support to and from the knife a plurality of times to produce a plurality of cuts, and automatic means for changing the level of the support between the times that the cuts are made to locate the cuts at different levels in the blank.

8. A machine of the class described having, in combination, a knife, a support for a blank, automatic means for feeding a blank to and from the knife a plurality of times to produce a plurality of cuts, said support being mounted for sliding movement with respect to the plane of the knife, and automatic means for imparting sliding movement to the support between the times that the cuts are made.

9. A machine of the class described having, in combination, a knife, means for feeding a blank to the knife to cause the knife to operate upon the blank and for then withdrawing it therefrom, and means for presenting the blank to the feeding means.

10. A machine of the class described having, in combination, a knife, means for feeding a blank to the knife to cause the knife to operate upon the blank and for then withdrawing it therefrom, a presenting slide, and means for operating the slide to present the blank to the feeding means.

11. A machine of the class described having, in combination, a knife, means for feeding a sole heel end foremost to the knife to cause the knife to make a cut in the heel end of the sole and then to be withdrawn therefrom, and means for presenting the sole to the feeding means.

12. A machine of the class described having, in combination, a knife, means for feeding a sole heel end foremost to the knife to cause the knife to make a cut in the heel end of the sole and then to be withdrawn there-

from, means for presenting the sole to the feeding means, and means for varying the time of presentation of the sole to the feeding means to vary the length of the cut.

5 13. A machine of the class described having, in combination, a knife, a support for a blank, means for feeding a blank to and from the knife a plurality of times to produce a plurality of cuts, and mechanism for presenting a blank over the support to the feeding means.

14. A machine of the class described having, in combination, a knife, a support for a blank, means for feeding a blank to and from the knife a plurality of times to produce a plurality of cuts, and mechanism operated by the feeding means for presenting a blank over the support to the feeding means.

15. A machine of the class described having, in combination, a knife, a support for a blank, means for feeding the blank to and from the knife a plurality of times to produce a plurality of cuts, a feed slide, and means for operating the feed slide a plurality of 20 times to present the blank to the feed mechanism.

16. A machine of the class described having, in combination, a knife, a feed roll, means for rotating the roll to a given extent first in a direction to present a sole to the knife and then in a direction to withdraw the sole from the knife, a feed slide, means for imparting reciprocation of a given extent to the feed slide, and blank-engaging means adjustable on the feed slide to determine the time of presentation of the blank to the feed roll and thereby the extent of the cut produced by the knife.

17. A machine of the class described having, in combination, a knife, a feed roll, means for rotating the roll a plurality of times first in one direction and then in the other to feed a blank a plurality of times to and from the knife, mechanism for presenting the blank to the feed roll, and means for operating said mechanism from said roll.

18. A machine of the class described having, in combination, a knife, and a table over which the work is fed to the knife, one edge 50 of the table being located in proximity to the edge of the knife, said table being angularly adjustable in a path at an angle to the plane of the knife to bring the edge of the table into parallelism with the edge of the knife.

19. A machine of the class described having, in combination, a knife having a straight operative cutting edge, a table over which the work is fed to the knife, and means for 60 mounting the table for swinging movement in a path at an angle to the plane of the knife to permit the edge of the table adjacent to the knife to be adjusted into parallelism with the edge of the knife.

65 20. A machine of the class described hav-

ing, in combination, a work support presenting an unyielding gaging edge over which a blank is fed, a knife having its cutting edge close to but above the gaging edge, an internally yieldable roll located to bear upon the work adjacent to the gaging edge, means for feeding the blank to and from the knife a plurality of times to produce in the blank a plurality of cuts, and means operating to change the relative levels of the gaging edge and the knife edge between the times the cuts are made.

70 21. A machine of the class described having, in combination, a knife, a support for the blank, and means for pressing the blank against the support, the support and the knife being relatively movable in the direction of extent of the plane of the support first to cause the knife to enter the blank and then to be withdrawn therefrom, said support and knife being also relatively movable in a direction at an angle to the first-named direction to relieve the pressure upon the blank during the withdrawal of the knife.

75 22. A machine of the class described having, in combination, a knife, a support for a blank and means for pressing the blank against the support and for causing relative movement between the support and the knife first to cause the knife to enter the blank and then to be withdrawn therefrom, said support and knife being also relatively movable to relieve the pressure upon the blank during the withdrawal of the knife.

80 23. A machine of the class described having, in combination, a knife, a support for a sole, means for pressing the sole against the support and for moving the sole over the support first to cause the knife to enter the sole to form a flap thereon and then to be withdrawn from the sole, and means for relieving the pressure upon the sole during the withdrawal of the knife.

85 24. A machine of the class described having, in combination, a knife, a stationary support for a blank, means for pressing the blank against the support and for feeding the blank over the support first in a direction to cause the knife to enter the blank and then in a direction to cause the knife to be withdrawn from the blank, and means for increasing the distance between the support and the pressing and feeding means to facilitate the withdrawal of the knife.

90 25. A machine of the class described having, in combination, a knife, means for causing a blank to be operated upon by the knife a plurality of times to form a plurality of flaps thereon, and means becoming operative between the operations of the knife to change the relative positions of the blank and the knife in such manner as to cause one flap to be thicker than another.

95 26. A machine of the class described having, in combination, a knife, a support for a

blank, means for first feeding the blank to and then withdrawing it from the knife to cause the knife to form a plurality of flaps on the blank, and means becoming operative between the cutting operations of the knife for changing the level of the support in such manner as to cause one flap to be thicker than another.

27. A machine of the class described having, in combination, a knife, means for causing the knife to enter a blank and to be withdrawn therefrom twice so as to operate twice upon the blank, means for maintaining the blank and the knife during the first operation in position to cause the knife to form a flap on the blank, and means for changing the relative positions of the knife and the blank prior to the second operation to cause the knife to split the flap formed by the first operation.

28. A machine of the class described having, in combination, a knife, a work table, means for feeding the work to the knife, a depending member by which the work table is supported, and a carrier upon which the depending member is mounted for movement in a path at an angle to the plane of the knife, said carrier being mounted for angular movement in a plane also at an angle to the plane of the knife.

29. A machine of the class described having, in combination, a knife, means for feeding a blank to the knife and withdrawing it therefrom to produce a flap thereon, and a member adjustable into different positions to cause the blank to be fed to and withdrawn from the knife a single time at a given level or a plurality of times at different levels as may be desired.

40. In testimony whereof I have signed my name to this specification.

WILLIAM C. BAXTER.
